TRAVELING BLOCK

Application filed May 19, 1928. Serial No. 278,951.

In the drilling of deep wells or in the lifting of any heavy machinery, or the like, it is frequently desirable to change the number of lines running to a traveling block so that a greater mechanical advantage can be obtained and a greater load lifted with the same power. Particularly in the drilling of wells it is frequently desirable to obtain a greater mechanical advantage in the traveling block in order that casing, tubing, or the like, can be more effectively lifted or lowered.

An object of our invention is to provide a traveling block with a removable sheave section which can be quickly and easily inserted or removed in the traveling block.

Another object is to provide a traveling block, the removable section of which always has the cable threaded thereover so that it can be brought into use in a minimum length of time and with very little labor.

Other objects, advantages, and features of invention may appear from the accompanying drawing, the subjoined detailed description, and the appended claims.

25 In the drawing:

Fig. 1 is a fragmentary view of a derrick including the crown block and showing our traveling block in connection therewith.

Fig. 2 is a side view of our block with the 30 removable section immediately above it.

Fig. 3 is an end view of our block.

Fig. 4 is a fragmentary side view of one of the pins.

Fig. 5 is an end view of the same.

35 Referring more particularly to the drawing, the numeral 1 indicates an oil well derrick of usual and well-known construction on the top of which any well-known type of crown block 2 is mounted. The crown block 40 is supported on suitable structural members 3, the details of which need not be described. Our traveling block 4 comprises a plurality of fixed sheaves 5 which are mounted on a heavy pin 6, which pin is secured in the side 45 plates 7, 8. The cable from the source of power (not shown) extends over the crown block 2 and thence around each of the various sheaves 5. As shown in the drawing, there would be three lines running from the sheaves 50 5 over three pulleys of the crown block.

A pin 9 extends between the side plates 7, 8 adjacent the bottom thereof, and a link 10 is secured thereto so that a hook, or the like, can be secured to the traveling block. Spacing plates 11, 11 extend between the sheaves 5 55 to space the same. A removable section 12 is provided which can either be secured to the side plates 7, 8 so that it moves with the rest of the traveling block, or it can be raised to the crown block and secured adjacent the 60 same at which time the remainder of the traveling block is released and a greater speed is obtained in the block although it will have less lifting capacity.

The removable section 12 comprises a pin 65 13 upon which a plurality of sheaves 14 are journaled. Spacing plates 15 are positioned on the outside of the sheaves 14 and between the same, thus providing a frame and also a spacing arrangement for the sheaves. An 70 upper guide pin 16 extends through the plates 15 the object of which will be further described. A pair of slots 17, 17 are cut in the side plates 7, 8 and holes 18, 19 are drilled through the side plates and communicate 75 with the slot 17 to expose the ends of the pins 13, 16 when the section 12 is in position in the block.

The removable section 12 is secured in place in the following manner: The pins 13, 16 are 80 rotatable in the section and the ends thereof are flattened on both sides, as at 20, so that the pins will just pass into the slot 17. The holes 18, 19 previously described, are of the exact 85 larger diameter of the pins so that when they are turned at right angles from the inserting position, the rounded sides of the pins will be at right angles to the slot, and thus the removable section will be securely held. Set screws 21, 22 extend through the side plates 90 against or into the pins to hold them against rotation.

When the removable section 12 is not in use, that is, when it is not secured to the traveling block, it is pressed tightly against the structural support 3 and is held in that position by suitable means. The cable, of course, still passes over the sheaves 14 and over the corresponding pulleys in the crown block so that 95 when it is desired to use this section it is 100

only necessary to lower it into the slots 17, then turn the pins 13, 16 so that they are locked in position, after which the traveling block is ready for use.

5 The pins 13, 16 can be readily rotated by a wrench which extends into a slot cut in the end of each pin, the wrench being extended through the holes 18, 19.

Having described our invention, we claim:

10 1. A traveling block comprising side plates, a plurality of fixed sheaves journaled between the side plates, a removable section including a plurality of sheaves journaled therein, and means to removably secure said removable section to the side plates.

15 2. A traveling block comprising side plates, a plurality of fixed sheaves journaled between said side plates, said side plates having slots therein adjacent the top thereof, a removable sheave section including a pin, sheaves mounted on the pin, said pin being adapted to extend into said slots, and means to secure said pin in the slots.

20 3. A traveling block comprising side plates, a plurality of fixed sheaves journaled between said side plates, said side plates having slots therein adjacent the top thereof, a removable sheave section including a pin, sheaves mounted on the pin, a second pin, frame plates extending between said first and last named pins both of said pins being adapted to extend into said slots and means to secure said pins in the slots.

25 4. A traveling block comprising side plates, a plurality of fixed sheaves journaled between said side plates, said side plates having slots therein adjacent the top thereof, a removable sheave section including a pin, sheaves mounted on the pin, a second pin, frame plates extending between said first and last named pins, both of said pins being adapted to extend into said slots, and means to secure said pins in the slots, said means comprising flattened faces on said pins whereby the pins are made to fit the slots in the side plates, said side plates having holes drilled therein through the slots to accommodate the greater diameter of the pins, and said pins being adapted to rotate in the holes to hold 30 the same against movement in the slots.

45 5. A traveling block comprising side plates, a plurality of fixed sheaves journaled between said side plates, said side plates having slots formed therein adjacent the top thereof, a removable sheave section including a pin, sheaves mounted on the pin, a second pin, frame plates extending between said first and last named pins, both of said pins being adapted to extend into said slots, and means 50 to secure said pins in the slots, said means comprising flattened faces on said pins whereby the pins are made to fit the slots in the side plates, said side plates having holes drilled therein through the slots to accommodate 55 the greater diameter of the pins, and said

pins being adapted to rotate in the holes to hold the same against movement in the slots, and set screws extending through the side plates against the pins to hold the same against rotation and a link secured to the 70 lower end of the side plates.

In testimony whereof, we affix our signatures.

CHARLES F. PIPPEN.
